UNITED STATES PATENT OFFICE

2,331,890

MINING AND RECOVERY OF POTASH COMPOUNDS

Roy Cross, Kansas City, Mo., assignor to Kansas City Testing Laboratory, Kansas City, Mo., a corporation of Missouri

Application July 5, 1941, Serial No. 401,104

8 Claims. (Cl. 262—3)

This invention relates to an improved process of recovering potassium salts from brines and ores containing them, and the present application is in part a continuation of my co-pending application Serial No. 267,506, filed April 12, 1939, which in turn is a continuation of my application Serial No. 136,178, filed April 10, 1937, now matured into United States Patent No. 2,161,800.

In the present methods of mining and recovering potash, ores are mined by shaft, room and pillar type of mining, analogous to ordinary shaft type coal mining. It is necessary to leave large amounts of the ore underground for pillars, walls, and ceilings, in order to assure safe working conditions and support. In the Carlsbad area in New Mexico, sylvinitite is mined in this manner but only 50% to 60% of the ore is removed from the deposits. As shown in my earlier application which uses a superheated liquor for dissolving potash salts from deposits, substantially all of the potash salts are removed from the deposits, leaving most of the sodium chloride in situ. In the course of this removal of potassium salts, a certain amount of sodium chloride is always present in the circulating liquor. One of the objects of the present invention is to provide a novel means of recovering the potassium chloride from the hot brine without recovery of this sodium chloride. Obviously, this is of advantage over the present method of elevating the ore mixture of potassium and sodium chloride to the surface, separating the potassium chloride and sodium chloride, and disposing of the sodium chloride. This disposal of sodium chloride is a source of considerable trouble at the present time, it being alleged that streams are polluted thereby.

In the present art, the recovery of potassium chloride from sylvinitite ore is done in two ways, one of which comprises a flotation and classification system dependent on selective wetability and on the difference in specific gravity between potassium chloride and sodium chloride, while the other depends upon a leaching of the sylvinitite ore with warm water at atmospheric pressure. The amount of equipment to produce 1,000 tons of potassium chloride per day by ordinary leaching is tremendous, since the brines must be recycled slowly in great quantities to dissolve the salts at this rate. Another object of the present invention is to provide a more efficient and economical method for producing potash from sylvinitite.

Other objects and advantages of the invention will be apparent by reference to the following de-

scription in conjunction with the accompanying drawings, in which:

Figure 1 is a diagrammatic or schematic illustration of a mining and extracting operation performed in accordance with the present invention;

Figure 2 is a chart showing the solubility of various materials that may advantageously take part in the practice of the invention as applied to sylvinitite;

Figure 3 is a diagrammatic or schematic illustration of another embodiment of the invention;

Figure 4 is a cross-sectional view taken along the line 4—4 of Figure 3;

Figure 5 is a cross-sectional view taken along the line 5—5 of Figure 3.

Figure 6 is an elevational view with parts broken away of a modified form of the invention illustrating a reflux vaporization vessel 40 of the type shown in Figure 1 in series with a precipitation tank 158 of the type shown in Figure 3.

For purposes of description, a typical operation on sylvinitite as the salt ore will be relied upon. Curves 3 and 4 in Figure 2 show the concentrations in pounds of potassium chloride and sodium chloride respectively, per 100 pounds of water. The respective illustrative maximum and minimum temperatures contemplated in this description, and the solubilities of the salt thereat are as follows:

Temperature, degrees F.	Lbs. salt per 100 lbs. water	
	KCl	NaCl
500	84	30.5
100	18	31.0
KCl recovered	66	—

It should be borne in mind that any increased concentration of the brine solution will precipitate sodium chloride.

In a mining operation, high pressure is of advantage in securing penetration into the bed as an aid to the high temperature of the solution for dissolving potash salt, although this is not so important in the extraction above ground from ores that have been broken up.

Referring to Figure 1, the operation in accordance with this invention as described now is the mining modification. Assuming the process to be in operation, one cycle will be described for recovering potassium chloride from an underground deposit of sylvinitite. A mother liquor, the composition of which is substantially a solution

saturated with respect both to sodium chloride and potassium chloride, is circulated into heater 34. This heater may conveniently be the type used in oil cracking units of the present time in which return bend connections of the tubes in the furnace allow access to the inside of the tubes. The mother liquor may be heated to between 300° and 600° F. The extractor units 52, 54, and 56 are by-passed by closing valves 70, 78, 86, and 92. The superheated mother liquor passes through valve 68 and conduit 36 to well 14 which is formed as follows: A well has been drilled into the potash bed, the bottom being approximately level with the bottom of the deposit. A large casing 16 is set in the well, the bottom of the casing being set approximately level with the top of the deposit. It is desirable to tightly seal the casing to the surrounding formation to prevent pressure leaks and also to insulate the casing. A surface pipe is often desirable. Inside of casing 16 is set smaller diameter production pipe 18. The bottom of pipe 18 is near the bottom of the potash bed and its top passes through pipe 16 above ground in a pressure tight joint. The superheated unsaturated brine passes downwardly in the annular space between pipes 16 and 18 and into the potash deposit where it dissolves potassium chloride. It should be assumed that a pool of liquor in the deposit is being substantially saturated with potassium chloride and that the hot brine is added to the pool. The hot brine is introduced to the bottom of the pool and gives a stirring action as it travels laterally across the pool. The equilibrium in the pool is disturbed and more potash is dissolved from the faces of the potash bed.

It is characteristic of potassium chloride that it takes up heat upon being dissolved, and therefore the brine becomes cooler and during its dissolving action travels downwardly along the face of the potash wall. Some radiation of heat takes place into the salt deposit and into the earth above and below the deposit. Also heat equal to the specific heat of both the potassium chloride being dissolved and the sodium chloride remaining, must be furnished. As the brine becomes saturated, it again travels horizontally at the lower part of the pool toward the well where it is released upwardly through production pipe 18. The brine has lost some of its original heat in radiation and in heat of solution of potassium chloride, and therefore is cooler as it travels upwardly in pipe 18, than is the downgoing liquor surrounding the pipe. This is an important arrangement because the upcoming brine is saturated with respect to potassium chloride and any cooling effect would precipitate potassium chloride and clog the production pipe. From production pipe 18, the superheated saturated brine passes through valve 80, conduit 66, and pressure release valve 38 into separator 40. Conduit 66 is well insulated or heated to prevent drop in temperature of the brine. The brine passes into the body of liquid in separator 40 and part of it immediately flashes into vapor, thereby cooling the brine and precipitating potassium chloride. Baffles 44 prevent the mechanical elevation of salt into condensing coils 32 and condenser 26. The hot brine may be introduced either above or below the level of the liquid in separator 40. The bottom of separator 40 is conical or hopper shaped to form a precipitated potash collecting zone 42. In the bottom of zone 42 is a conveyor arranged to pick up the precipitated potash and carry it to stock pile

20a. It should be noted that conveyor housing 48 preferably extends above the level of the pool of brine in separator 40 so that a draining action may be obtained.

When the vapor has flashed from the brine, it immediately comes in contact with vapor pre-cooling coils 32 and thence passes to condenser 26. The vapor is thus completely condensed and the condensate, being pure water, refluxes downwardly into the pool of the separator. This water condensate continually washes the condenser and coils and keeps them clear of salts. In some instances, it is desirable to have an auxiliary condenser 45 to insure complete refluxing of the vapors. This condenser may be cooled in any suitable manner.

The rate of flow of the liquor through separator 40 is slow enough that the desired minimum temperature can be reached. The cooled brine passes out of separator 40 through conduit 50 which is arranged to form a seal against the escape of vapors from the separator. The brine empties into tank 20.

The potassium chloride salt in zone 42 has come down substantially free from sodium chloride, due to the fact that the solubility of the sodium chloride is approximately the same at the low temperature of the pool as it was at the high temperature in the deposit. The material in the stock pile will contain some moisture which is in the form of the saturated potassium chloride-sodium chloride cold brine. The salt may be washed with a solution saturated with respect to potassium chloride, thus removing all sodium chloride. It is then dried and treated in a suitable manner for commercial sale.

Since it is desirable to maintain the pool of liquor in the potash deposit full of liquid, make-up fluid is added to tank 20 or at some suitable point. The make-up fluid is added in a volume equivalent to the volume of salts removed from the deposit. Brine seepage is also made up. The make-up fluid is ordinarily plain water. If it is convenient to make a sodium chloride brine for make-up fluid, this may be done in order that there will be no solution of sodium chloride from the deposit.

The cool brine is circulated from tank 20 by pump 24 through line 22 into condenser 26. The rate of circulation of the brine through condenser 26 is sufficiently fast to prevent the brine from absorbing more than enough heat to raise it to approximately its boiling point. Thus, the coolest brine is the cooling medium for the condenser in what ordinarily is the final refluxing stage of the condenser. An important feature of the invention is the fact that in many instances approximately the amount of brine in the system can be used as the cooling medium for condensing the vapors and absorb a considerable quantity of heat from the vapors prior to being reheated in the heater 34. This makes for economy of operation and equipment. From condenser 26 the brine passes through conduit 28 and is pumped by pump 30 at high pressure through vapor precooling coil 32 of the separator and thence is recycled through the system heretofore described. The circulating of the brine at high pressure through coil 32 is an important feature of the invention inasmuch as it allows sufficient precooling of the vapors by a brine which is already under pressure and therefore need not vaporize to allow a complete final absorption of heat from the vapors by condenser 26 where the cooling medium is at or near

atmospheric pressure. If precooling coil 32 is not used, condenser 26 must be larger in order to accomplish its purpose and a large amount of cooling agent other than the recycling brine is refluxed. The factors controlling this feature are the final temperature of the brine introduced into the potash bed and the amount of make-up water required to replace the volume of salt taken from the bed.

It is sometimes of advantage to pass the make-up fluid through auxiliary condenser 45 before adding it to the brine to be recirculated.

A modified application of the invention is an operation where the salt is dissolved from an ore which has been brought above ground and placed in extractors. For purposes of description it is assumed that the ore is sylvinitic and that the salt desired to be recovered is potassium chloride. Multiple extractors are used so that while the ore in two of the extractors is being contacted with brine, the third extractor may be filled with ore, thus making a continuous system. Any number of batteries of extractors may be used. Since the treatment of the brine in various stages has been described in connection with the mining operation, this description will describe a typical cycle in the recovery of the potassium chloride from sylvinitic ore.

Well 14 is by-passed from the system by closing valves 69 and 88. Mother liquor is superheated in heater 36 and passes through valve 18, conduit 58, and valve 72, into extractor 52. The rate of flow is such that the brine issuing from the extractor is substantially saturated with potassium chloride. The saturated brine circulates from extractor 52 through conduit 60, valve 74, conduit 76, valve 78, conduit 66, and pressure release valve 38, into separator 40. Potassium chloride crystallizes, settles and is carried out by conveyor 46 to stock pile 20a. The brine is cooled by reflux vaporization without concentration of the brine and the potassium chloride recovered as described in the mining operation. The cooled brine leaves separator 40 by conduit 50, falling into tank 20. It is then recirculated by pump 24 through conduit 22, through condenser 26, conduit 28, high pressure pump 30, and vapor precooling coils 32, to heater as previously described. In this instance, it is not necessary to add any considerable amount of make-up fluid since there is no requirement to fill a cavity as in the case of the mining operation.

When most of the potassium chloride has been extracted from extractor 52, valve 78 is closed and the brine passes through valve 82 into extractor 54, and thence to the separator 40 through conduit 62, valves 84 and 86, conduit 66, and pressure release valve 38, and the cycle is continued. In this manner unsaturated brine cleans up the ore residue in extractor 52 before entering extractor 54. When the ore in extractor 54 is nearly exhausted of potassium chloride, extractor 52 is by-passed and the superheated brine enters extractor 54 through valve 88 and exits through conduit 62 and valves 84 and 90 into extractor 56, valve 86 being closed. In this manner, the unsaturated brine passes through the mostly exhausted ore in extractor 54, thence through extractor 56, and out through conduits 64 and 96, valve 92, conduit 66, and pressure release valve 38, into the separator, and the cycle is continued. During this extraction, extractor 52 is recharged with fresh ore, the sodium chloride residue having been dumped into salt basin 98. When the ore in extractor 56 is nearly exhausted of potassium

chloride, extractor 54 is cut out of the system and the superheated brine enters extractor 56 through valve 100, exits through valves 84 and 102, conduit 106 and valve 104, into extractor 52, valve 92 being closed. From extractor 52, it continues through conduit 60, valve 74, valve 78, conduit 66, and pressure release valve 38, into separator 40, and the cycle is continued. In the meantime, the sodium chloride and other residue is dumped from extractor 54 and the extractor is recharged with fresh sylvinitic. In this manner, the most complete extraction of the ore may be obtained at a given rate of flow of the brine by thus continuously rotating the flow through the extractors and continuous operation is maintained.

Only one extractor may be used, or only two extractors may be used, the latter being the more desirable.

The novel method of cooling a saturated brine to obtain crystallization of a desired salt is a great improvement over the present art, particularly when it is combined with the feature of pre-heating the cooled brine by passing it in heat exchange relationship with the vapors to be condensed and passing the brine again through the heater. Equipment requirements are much smaller than in the present art. Higher circulation rates may be continually used and mechanical cooling difficulties are eliminated.

On properties already in operation by shaft mining methods, it is desirable to decrease the production costs of at least part of the ore mined by using the well type method covered in my co-pending application, and to also continue the use of the shaft mining equipment. Thus, it is convenient by using one system to extract salt from underground and from ores brought above ground, in a combination unit as shown in the drawings.

This invention has another feature which is important. This feature consists of adding to the saturated brine entering the separator or in the separator, a volatile vaporization agent having a boiling point lower than that of the brine. In this modification of the process the volatile liquid, in which potash not more than slightly soluble, is continuously added to the brine, continuously vaporized from the brine to eliminate the vaporization of water from the brine, condensed by suitable means, and continuously recycled into the brine for further cooling by vaporization. An arrangement of an outside condenser connected to the separator and means for recycling the vaporization agent is shown in Fig. 3. The cooled brine may be circulated through the condenser in heat exchange relationship with the vapors in the same manner as with the previously described system.

I sometimes cool the brine in two stages, the first being by reflux brine vapor cooling and the second being by the volatile agent vapor cooling. In this manner a lower final temperature of brine is reached and a greater yield of salt is obtained. This embodiment of the invention is illustrated in Figure 6 in which the precipitation tank 40 of Figure 1 is shown in series with the precipitation tank 158 of Figure 3. The conduit 50 is connected directly to the conduit 148 and all other numerals indicate like parts of the apparatus as previously described.

It is preferred that the volatile vaporization agent be one which is immiscible in the brine, although this is not a requirement.

A miscible vaporization agent may also be easily

separated from the brine leaving the separator 40 by distilling off any traces of the agent by a separate still treating the brine or by passing the brine in heat receiving relationship with the hot unsaturated brine leaving the condenser coils 26 or 32. Petroleum ether, butane or pentane may be used. Examples of other vaporization agents are sulfuric ether, benzene, alcohol, low boiling point gasoline hydrocarbons, acetone, etc.

In Figure 1, pre-cooling coil 32 has been illustrated diagrammatically as being in heat exchange relationship with the vaporizing zone of separator 40 which in turn is in direct communication with reflux condenser coils 26. Since the vapors are preferably brought into contact while still under pressure with pre-cooling coil 32, it will readily be recognized that coil 32 may be in a separate pressure chamber into which the vapors are first flashed and then released to the reflux condenser 26. Any other suitable modification or arrangement of the apparatus illustrated may be used to accomplish the same purpose, namely, contacting the flashed vapors while still under super-atmospheric pressure with the pre-cooling coil in which the circulating liquid is likewise under superatmospheric pressure. In this manner, the brine is depressured in several stages. An important feature of the system is that the hot brine containing salts is not brought in contact with cooling coils which would make a hard precipitate of the walls of the coils.

In carrying out the process described it is highly important to prevent precipitation of salts due to cooling in production pipes 18 and 66. As already indicated, this may be accomplished by heating the conduits to slightly unsaturate the solution contained therein. An alternative method is to maintain the rate of circulation of the dissolving material into and out of the potash deposit sufficiently fast to dissolve less potash than will form a saturated solution at the temperature of the production pipes above ground.

It is sometimes desirable to filter the potash brine before passing it into the separator in order to remove impurities such as dirt, iron compounds, etc., although usually settlement takes place in the deposit.

One of the preferred embodiments of this invention is illustrated in Figures 3, 4 and 5. As shown in Figure 3, in this embodiment a brine is superheated in a heater 110, then pumped through a conduit 112 controlled by a valve 114 by means of a pump 116 thence through a conduit 118, controlled by valves 120, 122 and 124 into a conduit 126. The conduit 126 passes through a casing 128 into a potash bed 130 and the superheated brine from the conduit 126 impinges against the far end 132 of the potash bed, causing a backward horizontal component of circulation along conduit 126 into the space between conduit 126 and casing 128. The liquid passing backward is substantially more saturated with respect to potash than the entering liquid. This more saturated liquid passes through an exit in the casing 128 into a conduit 134, thence through a conduit 136 to pump 138. Valve 124 and pump 138 coact to keep pressure of the liquid in the potash bed to a desired maximum, when desirable. Valve 124 is closed to the degree necessary to decrease hydrostatic head on the bed and pump 138 forces the saturated brine upwardly. In normal operation the valve 140 controlling conduit 136 is open and valve 141 is closed. The liquid in conduit 136 is pumped by means of pump

138 through conduit 142 controlled by valves 144 and 146 to a conduit 148 controlled by valve 150. When valve 153 is closed all of the liquid passes into conduit 148 through valve 150, which is normally open, to a distributing member 152, which distributes the hot liquid having a relatively high potash content in a body of liquid 154 below the liquid level 156. The body of liquid 154 is contained in what is termed a primary precipitation tank 158. The size of this tank may vary depending upon the volume of liquid being processed and other factors.

In the central part of the tank 158 is an open ended pipe or well 160 with one end disposed in the body of the liquid and the other end above the liquid level. Also disposed in the body of the liquid is a bubbler conduit 162 provided with a number of fine holes, spray nozzles, or similar devices 164 through which a volatile vaporizable liquid is passed and vaporized simultaneously or contemporaneously. This volatile liquid, preferably butane, or other volatilizable liquid obtainable as a by-product of the petroleum industry, serves as a cooling medium for the hot liquid introduced through conduit 148. In this manner the liquid introduced through conduit 148 and distributed through distributing member 152 is cooled almost instantly or immediately and the potash therein, being less soluble in the cold than the hot liquid, is precipitated and carried by means of a conveyor 166 or other similar device, in an upward direction in the manner shown so that as it moves upwardly in the conveyor, the entrained liquid tends to flow backward down the conveyor shaft 168. The remaining solid is continuously dropped onto a pile 170, or into any suitable container outside of the primary precipitation tank.

A conduit 172 passes through the wall of the tubular casing 160 and residual liquor is withdrawn from the primary precipitation tank 158 through this conduit. The residual liquor passing through conduit 172 enters conduit 178 through valve 272 controlled by the liquid level control device 268 by means of arms 270 and then passes to conduit 180, from which it enters a secondary precipitation tank 182 at a point below the liquid level 184, as illustrated in Figure 3. Valve 176 in conduit 174 is normally closed but in certain instances it may be desirable to bypass valve 272 by opening valve 176. In the secondary precipitation tank 182, further precipitation of salts occurs due to the influence of the cooling coils 186. Precipitated salts are carried from the bottom of the precipitation tank by means of a conveyor mechanism 188 and dropped onto a pile 190 in the manner illustrated. Residual mother liquor is drawn off by means of a conduit 192 and is pumped by means of a pump 194 through a conduit 196 into a condenser 198 where it assists in cooling and condensing the butane, or other volatilized liquid previously employed as a direct cooling medium in the primary precipitation tank 158. The mother liquor passing through the condenser 198 enters a conduit 200 through which it passes to a conduit 202 controlled by valve 204. Generally it is desired to return this mother liquor to the mining operation by passing it through a conduit 206, controlled by valve 210, to heater 110 where it is heated in tubes 212 and after being heated is pumped through conduit 112 by pump 116.

It will be understood that many different types of heaters may be employed and hence, the par-

ticular structure of the heater will not be described in detail. In some instances it may be desirable to by-pass a part or all of the liquid passing through conduit 142 to a conduit 214. In this latter event, the valve 204 is closed or partly closed and the valve 153 is open or partly open, permitting the by-passed liquid to go through heater 110 without cooling. Sometimes a pump is placed back of valve 153. Thus part of the saturated brine is cooled and another part is recycled to the potash bed to furnish more heat than is available from the amount of brine cooled and required to produce a given amount of potash.

As previously indicated, when the butane, or other volatilizable liquid enters the body of liquid 154 through pipes 162 and vaporizing elements 164, it is volatilized or vaporized, thereby acting as a refrigerant and simultaneously cooling the body of liquid 154 and the hot liquid entering through the distributing member 152. The volatilized vapors or gases rise upwardly in primary precipitation tank 158 and the mist is largely separated therefrom by a mist screen 216. The gases and vapors which pass the mist screen 216 enter a conduit 218 from which they pass into a suction chamber 220. From the suction chamber 220, gases or mixtures of gases and liquids, are passed through a conduit 224 controlled by a valve 226 and are compressed by means of compressor 228, after which they are passed through conduits 230 and 232 into a pressure condenser 234 where they are converted substantially completely to a liquid form. The volatilizable liquid passes from condenser 234 through a conduit 236 to a cylinder or reservoir 238 where it is held under pressure sufficient to maintain it in a liquid state under the existing temperature conditions. From the reservoir 238, the liquid is passed through conduits 240, 242, 244, 246 and valve 248 to the distributing conduit 162. In this manner the volatile liquid is continuously re-cycled in the process and the refrigerating effect thereof is utilized over and over again.

Figure 4 is a cross-sectional view of the primary precipitation tank taken along the line 4-4 of Figure 3, and Figure 5 is a cross-sectional view of the secondary precipitation tank taken along the line 5-5 of Figure 3.

In the foregoing description certain by-pass arrangements are not described. These arrangements are intended to be used under certain special circumstances or conditions. For instance, pump 116 is by-passed by conduits 250, 252 and 254, controlled by valve 256. It will be understood that the valve 256 is normally closed unless the by-pass arrangement is being used, in which case valve 114 would be closed. This by-pass arrangement may be employed where the pump is unnecessary, as, for example, where a source of a salt containing liquid is available under superatmospheric temperatures and pressures. Conversely, pump 116 may furnish pressure to circulate brine into and out of the potash bed to the surface where pump 138 is by-passed.

A second arrangement of conduits comprising conduits 258, 260 and 262 controlled by valve 264, is provided to circulate some hot unsaturated potash carrying liquid into conduit 142 to prevent precipitation on the way to the cooler 158. This is accomplished by partly opening valve 264, and partly closing valve 124. Valve 122 is open. This is an important feature of the invention. Since the only means of heating the potash bed and pool therein is by heat trans-

ferred from the brine circulated to the bed, the amount of heating in the bed is limited to heat available from the circulated brine. Furthermore, the amount of brine circulated to obtain a desired rate of potash production per unit of time is usually insufficient to furnish the desired amount of heat to the bed and pool. To overcome this difficulty part of the brine from the deposit is routed through the cooler and another part is by-passed and recycled through the heater without cooling, and thus transfers more heat in the potash bed. Another means of accomplishing this feature is to only partially cool and precipitate a large quantity of brine in the cooling stage of the operation, thus giving greater heat transfer in the bed than would be available if only the brine necessary to provide a given production rate of potash were used. This however requires handling larger volumes of liquor in the cooling stage. A pressure gauge 266 is provided in order to indicate the pressure of the liquid flowing in conduit 142. The liquid level in the primary precipitation tank 158 is maintained substantially constant by a liquid level control device 268 provided with arms 270 controlling the opening and closing of valve 272 in conduit 178. A similar device 274 maintains a substantially constant liquid level in tank 238 in conjunction with arms 276 and valve 278.

A typical illustration of the operation of the foregoing process is as follows: The solvent liquid passing through heater 110 is heated to a temperature of between 400° and 600° F. The pump 116 pumps the brine heated solvent liquid at about 50 gallons per minute under a maximum of about 500 lbs. per square inch pressure. The pump 138 pumps the solvent more saturated with respect to potash at about 50 gallons per minute under a maximum of about 600 lbs. per square inch pressure. Pump 194 is suitable for pumping the mother liquor at 50 gallons per minute under 500 lbs. per square inch pressure. The butane tank 238 is under a pressure of about 125 lbs. per square inch and the condenser 234 is under approximately the same pressure. The temperature of the more saturated liquor entering the primary precipitation tank from conduit 148 is around 300° to 500° F. The temperature of the liquor leaving the primary precipitation tank 158 through conduit 172 is around 200° F. The temperature of the brine leaving the secondary precipitation tank 182 through conduit 192 is around 60° to 100° F.

As illustrated, a portion of the butane in conduit 240 is directed through conduit 280 controlled by valve 282 to cooling coils 186 from whence it passes through conduit 284 to suction chamber 220. Thereafter, it is re-compressed by compressor 228 and condensed in condenser 198, as already described.

In practicing the invention it is possible to recover and mine the potash from a plurality of separate beds. As is well known, many potash deposits lie in multiple beds of comparatively thin character, for example, from 6 in. to 3 ft. in thickness. By ordinary methods these beds cannot be mined practically because working rooms of 6 to 10 ft. in height must be made and the cost of making such working rooms in order to obtain only 1 ft., or a few inches of potash is excessive. With the water mining and recovery method herein described, it is possible to mine multiple beds without difficulty. This is accomplished by boring a drill hole through the beds 70 and placing a steel casing therein properly ce-

mented. At predetermined points opposite the beds of potash pieces of a soft material are placed in the casing which are of such nature that they can easily be cut out and removed. These are usually of an aluminum type and one casing suitable for this purpose is called by the trade name "Securalloy." When the casing has been properly set and cemented, a drill bit and reamer are used to cut out the soft aluminum casing and any cement back of it thus opening up the formation at the desired horizon and leaving the casing tightly cemented otherwise. The liquid mining of the potash may then be carried out in the manner herein described. The particular method of dissolving the potash from the vein may be, for example, any one of the methods described in my U. S. application Serial No. 278,663, filed June 12, 1939, now Patent No. 2,251,916 issued August 12, 1941. By boring a series of holes in the casing at the proper levels, a plurality of potash deposits may be mined simultaneously. This is preferably accomplished by directing a jet of liquid laterally along the potash vein in the direction in which the potash is to be mined thereby progressively creating a channel in the potash and causing a backward component of circulation toward an exit conduit along or within the casing, or to another exit hole. Thus, where horizontal circulation is obtained, 5 beds of 3 ft. thickness will average the value of a single bed in the present operations having a 15 ft. thickness.

In some ores such as polyhalite, it is of great value to use a superheated solution of a salt for contacting the ore which, under heat and pressure, will convert the salt desired to a more soluble form. Thus, the use of sodium chloride or calcium chloride brine for the mining of polyhalite and obtaining potash and magnesium salts as chlorides rather than sulfates, is highly desirable.

The use of superheated brines or dissolving liquors for extracting reduces the production of calcium sulfate as an impurity and this is an important feature of the invention. Also, the mother liquor being a brine contributes a better heat transfer in the heater than would plain water.

In order to reduce corrosive action of the brine of the process, the pH of the brine may be raised by adding a convenient alkaline agent. Calcium or sodium hydroxide is usually satisfactory for this purpose. Inhibitors such as nicotine, arsenious oxide, quinoline ethiodide and the like are added to decrease or eliminate corrosive effects.

In attacking refractory ores, it is desirable to add CO₂ gas to the water being charged into the ores. In such cases the CO₂ is recovered by release of pressure and sent back into the well with the entering brine.

Where bromine and iodine occur with the potash ores, it is convenient to treat the brine at intervals with chlorine and steam to recover such bromine and iodine by fractional condensation.

Having thus described the invention, what I claim as new and desire to secure by Letters Patent of the United States is:

1. In a process of mining sylvinitc from subterranean deposits thereof and of recovering potassium chloride therefrom wherein a heated solvent liquor unsaturated with respect to potassium chloride is circulated in contact with said subterranean deposit of sylvinitc until said liquor

becomes more concentrated with respect to potassium chloride, the steps of passing said more concentrated liquor into a substantially constant volume body of a relatively cooler

5 mother liquor whereby potassium chloride is precipitated, refluxing and returning to the body of said mother liquor the vapors arising therefrom, separating precipitated potassium chloride from the body of said mother liquor, continuously re-
10 moving a portion of said mother liquor, reheating it and recycling it as a mining fluid in the process.

2. A process of mining potassium ores from subterranean deposits thereof and of recovering potassium compounds therefrom which comprises 15 heating an aqueous liquor which is a solvent liquor for potassium compounds when unsaturated with respect to said potassium compounds, passing said heated solvent liquor into a subterranean deposit of said ores, circulating said 20 solvent liquor in contact with said subterranean deposit until said liquor becomes more concentrated with respect to said potassium compounds, removing said solvent liquor from said subterranean deposit and passing it into a main body 25 of mother liquor, separating potassium compounds from said mother liquor, continuously removing a portion of said mother liquor from said volume of liquor and subjecting it to further cooling, separating a further amount of potassium compounds from said further cooled portion of said mother liquor, adding to said main body of mother liquor a water immiscible volatilizable liquid vaporizable at the temperature of said mother liquor, continuously volatilizing and condensing said solvent and using a portion of said solvent for the further cooling of the portion of mother liquor withdrawn from the main body thereof.

3. A process of mining sylvinitc and of recovering potassium chloride from subterranean deposits thereof which comprises heating an aqueous liquor which is a solvent liquor for potassium chloride when unsaturated with respect to potassium chloride, passing said heated solvent 45 liquor under superatmospheric pressures into a subterranean deposit of sylvinitc, circulating said solvent liquid in contact therewith until said liquor becomes relatively more concentrated with respect to potassium chloride, circulating a relatively more concentrated liquor out of the sylvinitc deposit, circulating part of said liquor to a depressuring and cooling zone and recirculating the other part of said potash liquor through a heating stage and thence through the sylvinitc deposit.

4. A cyclic process of mining potassium compounds from underground deposits thereof which comprises establishing a zone containing a main body of an aqueous mother liquor which is a solvent for said potassium compounds when unsaturated with respect thereto, withdrawing from said main body of mother liquor a portion thereof, heating said withdrawn portion of mother liquor whereby to produce a solvent liquor unsaturated with respect to the potassium compounds to be mined, passing said heated solvent liquor into a subterranean deposit of said potassium compounds, circulating said solvent liquor in contact with said subterranean deposit until said liquor becomes more concentrated with respect to potassium compounds, adding to the mother liquor at some stage during the cycle of operation a non-aqueous liquid more volatile than water, passing said more concentrated liquor into said main body of mother liquor, the

self-contained heat of said concentrated liquor vaporizing said added non-aqueous liquid thereby maintaining said main body of mother liquor at a relatively lower temperature than said more concentrated liquor, adding to said main body of mother liquor a sufficient amount of water to maintain the concentration of dissolved solids with respect to the volume of solvent liquor in said main body substantially constant, whereby the potassium compounds are precipitated without substantial precipitation of other compounds, and separating said precipitated potassium compounds from said main body of mother liquor.

5. A cyclic process of mining potassium compounds from underground deposits thereof which comprises establishing a zone containing a main body of an aqueous mother liquor which is a solvent for said potassium compounds when unsaturated with respect thereto, withdrawing from said main body of mother liquor a portion thereof, heating said withdrawn portion of mother liquor whereby to produce a solvent liquor unsaturated with respect to the potassium compounds to be mined, passing said heated solvent liquor into a subterranean deposit of said potassium compounds, circulating said solvent liquor in contact with said subterranean deposit until said liquor becomes more concentrated with respect to potassium compounds, adding butane directly to the zone containing the main body of mother liquor, passing said more concentrated liquor into said main body of mother liquor to continuously volatilize said butane, condensing and returning to said zone the butane thus volatilized, said main body of mother liquor thereby being maintained at a relatively lower temperature than said more concentrated liquor, adding to said main body of mother liquor a sufficient amount of water to maintain the concentration of dissolved solids with respect to the volume of solvent liquor in said main body substantially constant, at least a portion of said added water being derived by refluxing the vapors arising from said main body, whereby the potassium compounds are precipitated without substantial precipitation of other compounds, and separating said precipitated potassium compounds from said main body of mother liquor.

6. In a process of mining potassium chloride from an ore containing it wherein a heated solvent liquor unsaturated with respect to potassium chloride is circulated in contact with a subterranean deposit of the ore until said liquor becomes relatively more concentrated with respect to potas-

sium chloride, the steps of cooling said concentrated liquor in one stage by reflux vaporization from self-contained heat of the liquor, and cooling the liquor in a second stage by vaporization of an added water immiscible volatile agent at least partially by the self-contained heat of the liquor, while separating solid potassium chloride therefrom during said cooling stages.

7. In a cyclic process of the character described for recovering a potassium compound from an ore containing it, the steps which comprise establishing a zone containing a main body of a saline mother liquor, which is a solvent for said potassium compound when unsaturated with respect thereto, continuously withdrawing from said main body of mother liquor a portion thereof, treating said withdrawn portion to increase its dissolving action on said potassium compound, passing the treated portion into contact with said ore containing said potassium compound to thereby increase the concentration of the potassium compound therein, returning the more concentrated liquor to said main body of mother liquor, adding water to the main body of mother liquor to maintain the concentration substantially constant and to prevent the precipitation of other than potassium compounds, and separating the potassium compound from said body of mother liquor.

8. In a process of mining potassium compounds from subterranean deposits thereof and of recovering potassium compounds therefrom wherein a heated solvent liquor unsaturated with respect to the potassium compound is circulated in contact with said subterranean deposit containing the potassium compound until the liquor becomes more concentrated with respect to the potassium compound, the steps of passing said more concentrated liquor into a substantially constant volume body of a relatively cooler mother liquor whereby the potassium compound is precipitated, refluxing and returning to the body of said mother liquor the vapors arising therefrom, separating the precipitated potassium compound from the body of said cooler mother liquor, continuously removing a portion of said cooler mother liquor and continuously passing it into heat exchange relationship with said more concentrated hot liquor thereby to assist in cooling said more concentrated liquor and at the same time causing said cooler mother liquor portion to be heated, reheating said mother liquor portion further and recycling it as a mining fluid in the process.
